UNITED STATES PATENT OFFICE

2,299,173

WINDOW SHADE

Elmer F. Pidgeon, Spiceland, Ind.

Application January 22, 1942, Serial No. 427,801

5 Claims. (Cl. 156—10)

This invention relates to improvements in window shades and more particularly to improvements in shades adapted for use in "blackouts" or which are intended and capable of being used for totally excluding passage of light rays through a window opening.

More particularly, it is an aim of the invention to provide an improvement on the window shade construction as disclosed in U. S. Letters Patent No. 904,298, issued November 17, 1908, to adapt a window shade of this construction to use as a "blackout" shade.

A further and particular aim of the invention is to provide a flap which is normally disposed behind a folding shade of this construction and in which the folding shade can be rolled, when not in use, so that the entire shade will be in a compact roll and when in this condition will occupy only a very small area of a window opening so as not to materially reduce the passage of light rays therethrough.

Another aim of the invention is to provide a flap which will also function to protect the shade from dust and dirt when it is not in use and which is of particular importance in view of the fact that such shades are used infrequently.

Still another object of the invention is to provide a shade construction which may be made in any desired length or width and which can be mounted to overlap a window opening or which may be disposed therein and when disposed in the latter position can be sized so that the side edges thereof will hang flush against the jamb, due to the fact that no portion of the shade projects beyond the edges of the shade cloth or fabric.

Still another aim of the invention is to provide a window shade which can be constructed in one or more thicknesses of black cloth so as to render the shade completely opaque and which is still capable of being raised and lowered readily, which would not be possible, due to the thickness of the shade, if the shade were wound on a spring roller.

Other objects and advantages of the invention will hereinafter become more fully apparent from the following description of the drawing, which illustrates preferred embodiments thereof, and wherein:

Figure 1 is an edge view in elevation showing the shade in an extended position,

Figure 2 is a fragmentary side elevational view looking toward the back side of the shade and showing the upper part thereof in an extended position;

Figure 3 is a front elevational view showing the shade rolled and enclosed in its protective flap,

Figure 4 is an enlarged edge view in elevation showing the shade enclosed in the protective flap, and

Figure 5 is a fragmentary vertical sectional view of a portion of a modified form of the shade.

Referring more particularly to the drawing, wherein like reference characters designate like or corresponding parts throughout the different views, 10 designates generally a folding shade of substantially the same construction as the window shade disclosed in U. S. Letters Patent 904,298, and which includes a strip of black cloth or fabric 11 which is opaque or substantially opaque and which is provided at its bottom with a hem 12 and at its top with a hem 13, which hems are disposed transversely of the shade 10. Intermediate of its ends, the shade 10 is provided with a transversely disposed hem 14 and another transversely disposed hem 15 which is located above the hem 14 and spaced therefrom. Hems 14 and 15 are formed by strips of fabric 16 which are disposed on the outer side of the shade cloth 11 and which are stitched thereto as seen at 17. A shade bar 18 is contained in each of the hems 12, 13, 14 and 15 and extends substantially to the side edges of the shade cloth 11.

30 A supporting bracket 19 is adapted to be attached to the inner side or face of the top rail of a window frame, indicated at 20, for supporting a grooved pull cord roller and roller frame 21 on the frame 20 and above its opening 20'. The bracket 19 and the frame and roller 21 are 35 fully disclosed in U. S. Letters Patent No. 1,883,627, issued October 18, 1932, and a detailed description of these parts is therefore considered to be unnecessary. The frame and roller 21 is also attached to the shade bar 18 which is disposed in the hem 13 and is disposed on the forward side of said hem. A pull cord, designated generally 22, is suitably fastened at one end 40 thereof to the hem 16 and extends upwardly therefrom through an eye 23 which projects outwardly from the hem 15. The cord 22 then extends upwardly and outwardly over the roller which is mounted on the upper hem 13. The opposite end of the pull cord is passed inwardly 45 and over the roller which is supported by the bracket 19 and said last mentioned end is clamped between the frame 21, which is mounted on the hem 13, and the bar 18, which is disposed in said hem, or may be otherwise secured to the upper end of the window shade 10. The pull cord

22 also includes an elongated loop which depends from the two rollers and which includes a portion 24 which depends from the roller which is mounted on the hem 13 and a portion 25 which depends from the roller which is supported by the bracket 19.

As seen in Figure 1, the distance between hems 12 and 14 is substantially one-half the distance between the hems 14 and 15 and the hems 13 and 15. Consequently, by pulling downwardly on the cord portion 24, the first mentioned end of the cord 22 is drawn upwardly to raise the shade 10 from the hem 14, with the cord 22 sliding through the eye 23, until the hem 14 moves into engagement with the eye 23, after which the shade 10 will also be raised from the hem 15 until the hems 14 and 15 are nested with the hem 13, in which position loops of the shade fabric 11, between the hems 13 and 15 and the hems 14 and 15, will depend downwardly substantially the same distance that the portion of the shade 10, between hems 12 and 14, will depend from the hem 14. With the shade thus folded, it will cover approximately one-fourth of the window opening 20' so as to obstruct the passage of light rays therethrough. It will likewise be readily apparent that the shade 10 while folded, extended or partially extended, can be raised by pulling on the cord portion 25 or lowered by paying out the cord portion 25. The grooved rollers supported in the frames are of the type, now well known, which can be utilized for clamping the pull cord by drawing the cord out of alignment with the center of the roller. In view of the disclosure in the aforementioned U. S. Letters Patent No. 904,298, a further description of the part of the shade 10, which has been previously described, is considered unnecessary.

A novel feature of the present invention resides in the provision of the flap 26 which is preferably formed by the upper end of the shade fabric 11 and which depends from the hem 13 and is disposed behind the shade 10. The flap 26, could, if desired, obviously be formed of a separate piece of fabric stitched or otherwise secured to the back part of the hem 13. The lower edge of the flap 26 is provided with a plurality of laterally spaced eyes 27, each of which is oblong, and said lower end or edge of the flap 26 is preferably provided with a hem 28 for reinforcing the portion thereof in which the eyes 27 are formed. A plurality of laterally spaced turn buttons 29 are mounted on the hem 13 and project from the front side thereof. It will thus be readily apparent that when the shade 10 is in a raised, folded position that said shade can be rolled upwardly after which the flap 26 can be disposed therearound, as seen in Figures 3 and 4. The turn buttons 29 are located to be received by the eyes 27 for fastening the turn buttons to the eyes, in a conventional manner, by a ninety degree turn of the turn buttons 29, and thereby connect the lower, free end of the flap 26 to the forward side of the hem 13. The flap 26 extends from side edge to side edge of the shade fabric 11, as seen in Figures 2 and 3, so that the shade 10 will be enclosed therewithin except for the edges thereof which will be disposed in the open ends of the roll formed by the flap 26. When the shade 10 is thus rolled, as seen in Figures 3 and 4, it will be readily apparent that it will cover a portion of the window opening 20' substantially less than the amount of the window opening which is covered by the folded shade 10. Consequently, the flap 26 will not only protect the shade from dust

and dirt while not in use, but will also hold the shade in a compact rolled condition to reduce materially the extent that it will obscure the passage of light rays through the window opening with which it is associated.

Obviously, other forms of separable fasteners could be substituted for the separable fasteners formed by the parts 27 and 29, such as conventional separable snap fasteners.

10 In the drawing, the shade 10 is shown mounted on the inner side or face of the window frame 20 and it will be readily apparent that it can overlap the jambs, top rail and sill thereof to any extent and, obviously, the more the shade overlaps the frame the more effectively it will obscure and prevent the passage of light rays through the window opening. The shade may obviously also be mounted directly within the window opening and as it is provided with no portions which project beyond the side edges of the shade fabric 11, it will be apparent that said edges may engage flush against the jambs of the window frame to seal the window opening against the passage of light rays. The shade cloth, in order to be even substantially opaque must be relatively thick, and the thickness of the material makes it impractical for use with conventional spring wound window shade rollers so that a folding shade of the type herein shown is far more practical. As flexible fabrics cannot be made entirely opaque, in order to provide a shade which will prevent the passage of all light rays, the shade cloth must be of at least two thicknesses or plies, as illustrated in the modified form as shown in Figure 5 and 15 30 35 40 45 50 55 60 65 70 75 which includes the plies 11' which are stitched together as seen at 17' to form the hem 14', and similarly to form the hem 15', not shown. When the shade 10' is thus constructed of two plies of cloth, it will function in the same manner as the shade 10, and the flap 26 thereof is preferably formed of only a single ply although it may be of two plies, if desired. Where two plies are thus employed, fabric having a nap side can be used by positioning the two plies with the nap sides toward one another. If desired, the hem 14' can also be formed similar to the hems 14 and 15 by attaching a strip of fabric 16 to the outer side of the outer ply 11'.

Various modifications and changes in the construction and arrangement of the parts shown and described, are contemplated and may obviously be resorted to, provided they fall within the spirit and scope of the invention as herein-after defined by the appended claims.

I claim as my invention:

1. A window shade comprising a strip of fabric having longitudinally spaced transversely disposed hems each containing a shade bar, one of said hems being disposed at each end of the shade, a shade cord pulley attached to the shade bar and hem, forming the upper end of the shade and disposed on the outer side thereof, a pull cord attached at one end to the next to the bottom bar and slidably connected to the bars disposed between the bottom bar and said upper bar, said cord being trained over said pulley, a cord pulley adapted to be attached to a window frame above the shade, said pull cord, adjacent to its opposite end, being trained over the last mentioned pulley, and having said opposite end anchored to the upper end of the shade, so that the shade can be raised and lowered bodily by a pull on one portion of the cord and so that the lower portion of the shade can be raised relatively to the upper end thereof and

arranged in a plurality of folds, by a pull on the other portion of the cord, and said fabric strip having an end depending from the upper hem and disposed behind the shade and forming a flap in which the shade can be rolled and substantially enclosed, when in a folded position.

2. In combination with a window shade of the type having means whereby the shade can be raised or lowered in its entirety and its lower end raised or lowered in folds relatively to its upper end; a fabric flap disposed behind the shade and attached at its upper edge to the upper end of the shade, said flap being adapted to be looped around the shade, when the shade is folded, for substantially enclosing the shade therein.

3. An article as in claim 2, and fastening

means carried by the lower edge of the flap and the upper end of the shade for connecting the lower edge of the flap to the top of the shade to form a loop of the flap in which the shade is contained.

5. An article as in claim 2, and fastening means carried by the lower edge of the flap and the upper end of the shade for connecting the lower edge of the flap to the top of the shade to form a loop of the flap in which the shade is contained, said fastening means being attached to the outer side of the upper end of the shade.

10 15 5. An article as in claim 2, said flap forming an end of the strip of fabric forming the shade.

ELMER F. PIDGEON.
